Assistant Examiner—Frank Martinez

[57] CLAIM

The ornamental design for a truck tailgate protector, as shown and described.

DESCRIPTION

FIG. 1 is a perspective view of the truck tailgate protector showing my new design;

FIG. 2 is a left end view thereof;

FIG. 3 is a right end view thereof;

FIG. 4 is a front elevational view thereof;

FIG. 5 is a rear elevational view thereof;

FIG. 6 is a top plan view thereof; and,

FIG. 7 is a bottom plan view thereof.

The straps are shown broken to indicate indeterminate length.
